United States Patent Office

Des. 183,473
Patented Sept. 2, 1958

183,473

PITCHER

Robert J. Willis, Woodland Hills, Calif., assignor to The Plas-Tex Corporation, Los Angeles, Calif., a corporation

Application February 18, 1958, Serial No. 49,693

Term of patent 14 years

(Cl. D44—21)

I claim:

The ornamental design for a pitcher, substantially as shown.
